A. SCHMID.
LIQUID DISPENSING APPARATUS.
APPLICATION FILED APR. 27, 1914.

Patented July 31, 1917.

Witnesse,
M. J. Kelling
H. P. Aldwood.

A technical drawing of a rectangular frame with a central horizontal slot. The left side of the frame is hatched with diagonal lines. The word "Inventor" is written in cursive script above the frame. Below the frame, the name "Arthur Schmid" is written in cursive, followed by "by P. Singer Atty" in a smaller, stylized font.

UNITED STATES PATENT OFFICE.

ARTHUR SCHMID, OF ZOLLIKON, NEAR ZURICH, SWITZERLAND.

LIQUID-DISPENSING APPARATUS.

1,234,939.

Specification of Letters Patent. Patented July 31, 1917.

Application filed April 27, 1914. Serial No. 834,777.

To all whom it may concern:

Be it known that I, ARTHUR SCHMID, a citizen of the Republic of Switzerland, residing at Zollikon, near Zurich, in the Canton of Zurich, Republic of Switzerland, have invented certain new and useful Liquid-Dispensing Apparatus; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of the invention is a liquid dispensing apparatus especially intended for the dispensing of non-alcoholic liquids or liquids containing only a very small percentage of alcohol in order to prevent the beverage from getting stale or from deteriorating by standing.

With the known apparatus of this kind the liquid is subjected to the pressure of a gas, for instance carbonic acid which is either pressed directly into the cask or receptacle, or a receptacle charged with the gas is placed inside of the cask from which the gas is fed to the liquid by force or automatically.

A number of devices have been invented having as their object to retard the decomposition or deterioration of beverages as for instance, milk by the use of nitrogen.

In contradistinction thereto, the object of the present invention is to provide a liquid dispensing apparatus, which serves to keep the beverage potable for a considerable length of time. With this end in view, the receptacle containing the liquid to be dispensed is provided with a receptacle containing the gas from which the latter is dispensed in quantities sufficient to replace the quantity of liquid dispensed, so that the liquid is constantly under pressure and cannot lose its potability, no matter how long time it requires to dispense the entire contents of a cask, etc.

In the accompanying drawing:

Figure 1 is a vertical section through the preferred form of the apparatus.

Fig. 2 shows a modified form of the apparatus.

Fig. 3 shows the apparatus applied to a cask or barrel.

The apparatus illustrated in Fig. 1 con-

sists of a tap 2 adapted to be tightly screwed into the bung-hole of a cask. Securely attached to the tap 2 is one of the branches of a siphon tube 6 reaching nearly to the bottom of the cask.

The gas is preferably contained in a receptacle 3 (Fig. 3) attached to the body 22 and passes through the filter 17, the channel 18 and into the chamber 15 of the reducing valve working in the well known manner. From this chamber the gas at reduced pressure flows through the vertical channels 19 and 20 into the cask. The gas container 3 has such a capacity that one filling is sufficient to expel the entire contents of the cask.

As soon as the pressure is reduced by dispensing one or more drinks, the arm 12 moving between the springs 13 and 14 and tightly secured to the membrane 16 opens the gas channel until the pressure in the cask becomes normal.

The opened tap, shown in Fig. 1 is closed by turning the stop cock 9 by means of the handle 10, so that the dispensing channels 8¹ and 8² come out of communication with the parts 7¹ and 7² of the channel.

For the purpose of sterilizing the apparatus and the cask, the nozzle 7³ is connected with a source of steam which upon the proper operation of the cock 9 will pass through channels 7 and the siphon branch 6 into the barrel or cask 1 and properly sterilize the same by destroying all bacteria contained in said apparatus or barrel.

By properly manipulating the cock 9, the channel 8¹, 8² will be brought into communication with the channels 7¹, 7² and thereafter with the radial bore 11 of the tap 2 and the steam supply channel 7³ so that the steam will pass into the gas chamber 15 and through the channels 19 and 20 into the cask 1.

By pushing the arm 12 inwardly by means of a pin or the like, introduced through the spring 14, part of the steam will flow through the channel 18 and the filter to the outside.

The container for the gas under pressure is connected to the apparatus 2 by means of a pressure pipe 24 (Fig. 3) and is also sterilized during the sterilization of the gas passages. In this manner the apparatus is thoroughly sterilized and as it is constantly held under a pressure above the atmospheric pressure, it will be impossible that air and

microbes can enter the apparatus after it has been once sterilized and placed under the pressure of the gas.

Fig. 2 shows a modified form of apparatus in which a reducing valve is used. As outlet for the liquid a lift valve in place of a tap is used. The valve can be operated by means of the knob 10. To sterilize the apparatus, steam can be used in the same manner as described with respect to Fig. 1. The steam pressure opens the recoiling valve 25 toward the side of the gas, which side is sterilized as described in Fig. 1.

The retail pouring out of sterile drinks in optional quantities without infecting the contents and at a constant pressure is made possible with both of the described constructions provided the compressed gas receptacle contains enough gas to empty the cask of all the liquid.

What I claim is:—

1. In combination with a hermetically closable liquid receptacle, a liquid delivering device, a sterilizable gas pressure regulator for automatically regulating the flow of a pressure gas into the liquid receptacle in proportion to the quantity of the dispensed liquid, said regulator having a spring-pressed diaphragm with a closing member, a high pressure gas receptacle outside of the liquid receptacle, a connection permitting the sterile joining of the gas receptacle to the gas regulator and means for allowing the lifting by hand of the closing member of the diaphragm of the regulator from the opening admitting the high pressure gas into the regulator to allow disinfecting agents to pass for sterilizing purposes.

2. In combination with a hermetically closable liquid receptacle, a sterilizable gas pressure regulator for automatically regulating the flow of a pressure gas into the liquid receptacle in proportion to the quantity of the dispensed liquid, said regulator having a spring pressed diaphragm with a closing member, a high pressure gas receptacle outside of the liquid receptacle, a connection permitting the sterile joining of the gas receptacle to the gas regulator, means for allowing to lift by hand the closing member of the diaphragm of the regulator from the opening admitting the high pressure gas

into the regulator to allow disinfecting agents to pass for sterilizing purposes, and a liquid delivering device with a communication to the gas side interrupted during the normal use of the liquid delivering devices and enabling disinfecting agents to pass in order to sterilize all passages being in connection with the inside of the liquid receptacle.

3. In combination with a hermetically closable liquid receptacle, a liquid delivering device, a sterilizable gas pressure regulator for automatically regulating the flow of a pressure gas into the liquid receptacle in proportion to the quantity of the dispensed liquid, said regulator having a spring-pressed diaphragm with a closing member, a high pressure gas receptacle outside of the liquid receptacle, a connection permitting the sterile joining of the gas receptacle to the gas regulator and a gas filter placed in the connection between the gas-receptacle and the gas pressure regulator and qualified to be sterilized.

4. In combination with a hermetically closable liquid receptacle, a sterilizable gas pressure regulator for automatically regulating the flow of a pressure gas into the liquid receptacle in proportion to the quantity of the dispensed liquid, said regulator having a spring pressed diaphragm with a closing member, a high pressure gas receptacle outside of the liquid receptacle, a connection permitting the sterile joining of the gas receptacle to the gas regulator, means for allowing to lift by hand the closing member of the diaphragm of the regulator from the opening admitting the high pressure gas into the regulator to allow disinfecting agents to pass for sterilizing purposes and a gas filter placed in the connection between the gas-receptacle and the gas pressure regulator and qualified to be sterilized.

In testimony whereof, I have signed my name to this specification in the presence of two subscribing witnesses.

ARTHUR SCHMID.
